UNITED STATES PATENT OFFICE.

EDWARD F. CRANE, OF NEWARK, NEW JERSEY.

REINFORCING-BAR FOR CEMENTITIOUS BODIES.

No. 820,704.

Specification of Letters Patent.

Patented May 15, 1906.

Application filed August 2, 1905. Serial No. 272,287.

To all whom it may concern:

Be it known that I, EDWARD F. CRANE, a citizen of the United States, and a resident of Newark, in the county of Essex and State of New Jersey, have invented certain new and useful Improvements in Reinforcing - Bars for Cementitious Bodies, of which the following is a specification.

In the use of cementitious substances, such as concrete, for building and other purposes it is customary to reinforce and impart a desired tensile strength to the same by embedding therein suitable metallic members, such combination of metallic reinforcing members with the cementitious body resulting in the formation of a composite structure capable of resisting both compressive and tensile strains to a very great degree.

When metallic members are thus combined with or embedded in a cementitious body, it is desirable that a complete adhesion and union of the two elements should be obtained to prevent movement of one relatively to the other, and this is usually accomplished by providing the metallic reinforcing members with a series of transversely-arranged shoulders for interlocking engagement with the cementitious body. These interlocking shoulders are usually formed by a distortion of some character of the bar constituting the reinforcing member, and such distortion in some instances is of such character as to result in a lessening of the tensile strength of the bar. It is obviously desirable, however, that all the metal entering into or forming part of the bar should be so disposed as to develop its full tensile strength, and it has therefore been the object of my present invention to provide a reinforcing-bar of the character referred to in which the metal will be so disposed as to provide transversed shoulders for interlocking engagement with the cementitious body and at the same time develop practically its full tensile strength.

To this end my invention consists in providing a metallic reinforcing bar or member for cementitious bodies having a plurality of parallel spirals of different depths with more or less abruptly-formed shoulders between the same for interlocking engagement with the cementitious body, the said spirals being so arranged that the bar will be of uniform cross-sectional area throughout its length, and therefore of uniform tensile strength.

Referring now to the accompanying draw-

ings, forming part of this specification, Figure 1 is a perspective view of a reinforcing-bar embodying one form of my invention. Fig. 2 is a plan of the same combined with a cementitious body, which latter is partially removed from the bar to disclose the latter, and Fig. 3 is a cross-section of the bar through line 3-3 of Fig. 2.

Similar reference characters designate like parts in the several figures of the drawings.

In the drawings, *b* designates generally a reinforcing bar or member formed in accordance with my invention, and *c* designates the concrete or other cementitious body in which, as shown in Fig. 2, the said metallic reinforcing-bar *b* is adapted to be embedded.

The metallic bar *b*, in accordance with my invention, as hereinbefore stated, is formed with a plurality of parallel spirals of different depths, having more or less abruptly-formed shoulders between the adjacent spirals for interlocking engagement with the cementitious body, the said spirals, as shown in the bar illustrated, being three in number and indicated at 4, 5, and 6, and the said interlocking shoulders between the adjacent spirals being two in number and indicated at 7 and 8. A bar thus formed will be of uniform cross-sectional area throughout its length, and therefore of uniform tensile strength, and the transversely-arranged shoulders formed by the varying depths of the several spirals present such a considerable surface for interlocking engagement with the concrete or other cementitious body as to prevent any possibility of movement of one relatively to the other.

The number of spirals with which the reinforcing-bar is provided may of course be varied, as it will be understood that in some instances where a light bar is to be used in connection with a small body of concrete which is not to be subjected to any considerable degree of strain, a less shoulder area for interlocking engagement with the concrete body will be required than in a case where a larger reinforcing-bar is to be used in connection with a larger concrete body and one adapted to be subjected to heavier strains. The number of spirals may therefore be varied to provide different areas of interlocking shoulder-surface, according to the size of the bar or the work to which it is to be applied, without departure from my invention.

What I claim is—

1. A one-piece metallic reinforcing-bar for cementitious bodies having a plurality of substantially flat spirals of different depths, as and for the purpose set forth.
2. A metallic reinforcing-bar having a plurality of substantially flat spirals of different depths with abruptly-formed shoulders between the spirals, as and for the purpose set forth.
3. A metallic reinforcing-bar having a plurality of spirals of different depths, said spirals having flat surfaces arranged parallel to the axis of the bar with shoulders between the flat faces of the adjacent spirals, as and for the purpose set forth.
4. A metallic reinforcing-bar for cementitious bodies having a plurality of parallel

spirals of different depths with an abruptly-formed shoulder between the adjacent spirals, for the purpose set forth. 20

5. A composite structure, consisting of a cementitious body in combination with a metallic reinforcing-bar embedded therein, the said reinforcing-bar having a plurality of parallel spirals of different depths with an abruptly-formed shoulder between the adjacent spirals. 25

Signed at New York, in the county of New York and State of New York, this 26th day 30 of July, A. D. 1905.

EDWARD F. CRANE.
